UNITED STATES PATENT OFFICE

PAUL F. BOE E, OF ST. PAUL, MINNESOTA, ASSIGNOR TO WALDORF PAPER PRODUCTS COMPANY, OF ST. PAUL, MINNESOTA, A CORPORATION OF MINNESOTA

SHIPPING CONTAINER FOR INDIVIDUAL BATTERIES

Application filed April 13, 1928. Serial No. 269,689.

REISSUED

This invention relates to improvements in containers for dry cells or batteries of the larger, rectangular type used principally for radio receiving sets. In a copending application, Serial No. 181,746, filed by Paul A. 5 Schilling and myself on April 7, 1927, a two piece slide or "Lambert" for such batteries is described and the present invention is an improvement thereon.

Such batteries have projecting terminals 10 which are apt to be broken in transit or handling and their weight is sufficient to compress or crush the corrugations or corrugated board if substantial movement is permitted in the shipping package. Thus 15 I have discovered that while a limited degree of resiliency in the package is required to prevent breakage of the battery, an excessive amount of cushioning is undesirable 20 because it permits shifting of the contents, and gradual compression of the corrugations under the resulting impact, until the protection is impaired or destroyed. The present invention is designed to meet these conditions.

25 It is my object to reduce the cost of such containers and at the same time to increase their strength and the protection to the goods by constructing the outer casing from solid fibre board and the inner cushion member from corrugated sheet material.

A further object is to provide an improved guard for the battery terminals which is positioned between the battery and the 35 container to maintain the terminals in spaced relation to the cover.

The invention will be best understood by reference to the accompanying drawings in which Figure 1 is a perspective view of my 40 improved container with the battery and inner cushion member partially withdrawn from the outer sleeve or casing; Fig. 2 is a vertical, longitudinal section through the container with the parts in closed position 45 and with a battery in place therein and Fig. 3 is a plan view of the same with the cover open.

The container has an outer, tubular casing 4 which is formed from solid fibre board, 50 open at its top and bottom ends to receive

an inner corrugated member which is insertable from either end of the casing 4. The inner member is formed from a single rectangular blank of corrugated board which is creased transversely to form two parallel side walls 5 and 6, a bottom wall 7, cover flap 8 and flange 9 extending along the normally free edge of the cover flap 8. The battery 10, to be inserted in the container, is of the common rectangular type having projecting terminals 11 on its top. To protect these terminals a hollow, tubular guard 12 is made integral with one end of the blank constituting the walls 5, 6 and 7. The guard 12 is an extension on the normally upper end of the side 5 which is folded to form four rectangularly disposed walls 13, 14, 15 and 16. The wall 13 is arranged to abut against the inner surface of the cover flap 8, while the wall 14 extends downward, perpendicular to the cover flap 8 and abuts against the terminals 11. The wall 15 rests upon the top of the battery 10 and the fourth side 16 is normally positioned parallel to the side 5 and wall 14. Thus the guard consists of walls 13, 14, 15 and 16 arranged to abut respectively against the cover 8, terminals 11, top of the battery 10 and inner surface of the side 5. The cover flange 9 and side 5 have overlapping portions 9a and 5a respectively in which the corrugations of the sheet are flattened so that the combined thickness of these overlapping portions is equal to the normal thickness of the corrugated sheet.

In use, a battery 10 is inserted in the inner, corrugated member of the container with the side walls 5 and 6 covering the opposite, wider sides of the battery and the bottom of the battery resting on the bottom 7 of the corrugated blank. Now the guard member 12 on the upper edge of the side 5 is folded to hollow, rectangular form upon the top of the battery and the cover is closed as indicated in Figs. 1 and 2. The battery thus covered by the inner, corrugated member may now be inserted in the tubular casing 4 as indicated in Fig. 1 and the cover flange 9 inserted between said casing and the battery. The cover flap 8 is frictionally held in closed 100

position by the overlapping portions 9a and 5a which fit snugly between the battery and casing 4. For the final sealing, binding strips of the common type held in place by adhesive 5 may be applied over the edges of the cover flap 8 and bottom 7.

When the container is thus closed, the guard 12 for the terminals 11 is securely held in rectangular form because each of the four 10 walls 13, 14, 15 and 16 is confined by one of the several abutments for their outer surfaces. Obviously the walls 14 and 16 retain the terminals 11 in spaced relation to the cover flap 8.

15 As is well known corrugated board has considerable rigidity and strength to oppose forces tending to crush it longitudinally of the corrugations. Thus the sides 14 and 16 form rigid brace members which are not compressible under the weight of the batteries. An excessive amount of cushioning is avoided by my arrangement because the walls 14 and 16 are less compressible than the equivalent thickness of sheets laid flat upon the 25 top of the battery.

The container has the further advantage of permitting the cover to be opened for inspection and testing purposes without removing the guard 12. Tests of containers made according to this invention have shown that the device affords greater protection to the batteries and withstands harder usage than containers having outer casings of corrugated board but otherwise of the same construction as that shown and described.

Having described my invention what I claim is new and desire to protect by Letters Patent is:

1. A container for a battery having projecting terminals on its top to be protected, 40 comprising an outer tubular casing open at its top and bottom ends and formed from solid fibre board, an inner cushion member formed from a rectangular sheet of corrugated board folded to extend upon the bottom and two sides of a battery therein and forming a cover flap and a rectangular hollow guard for the terminals of said battery confined and supported at four sides respectively by said terminals, battery, cover and cushion member.

2. In a container for a battery having projecting terminals on its top to be protected, a cushion member formed from a sheet of 55 corrugated board folded to extend upon the bottom and two sides of a battery therein and also forming a tubular, rectangular guard for the terminals of said battery, said guard having the corrugations on at least 60 two walls extending perpendicularly to the top of the battery and said walls being supported against collapse by engagement of one of them with said terminals, and means for confining said guard on the top of the battery.

65 3. In a container for a battery having pro-

jecting terminals on its top to be protected, a cushion member formed from a sheet of corrugated board folded to extend upon the bottom and two sides of a battery therein and forming a cover flap and a tubular guard for the terminals of said battery, said guard having the corrugations on at least two walls extending perpendicularly to the top of the battery and said walls abutting respectively against said terminals and the inner surface of the cushion member, said cover flap being arranged to confine said guard on the top of the battery.

In testimony whereof, I have hereunto signed my name to this specification.

PAUL F. BOEYE.
